UNITED STATES PATENT OFFICE.

LEONIDAS F. STOREY, OF ST. PAUL, MINNESOTA, ASSIGNOR OF ONE-HALF TO WATEROUS FIRE ENGINE WORKS, OF ST. PAUL, MINNESOTA, A CORPORATION OF MINNESOTA.

HYDRANT.

Application filed February 9, 1925. Serial No. 8,041.

My invention relates to the type of hydrant shown and described in my pending application for United States patent filed May 2, 1923, No. 636,165, and the particular object of my present invention is to incorporate certain improvements in the details of construction which have been suggested by the difficulties arising from the care and use of the hydrant of my former application.

The invention consists generally in various constructions and combinations all as hereinafter described and particularly pointed out in the claims.

15 In the accompanying drawings forming part of this specification,

Figure 1 is a vertical sectional view of the lower portion of a fire hydrant showing my improved waste water mechanism applied thereto, the waste water port being shown in its open position;

Figure 2 is a similar view showing the position assumed by the parts when the hydrant valve is opened;

25 Figure 3 is a sectional view on the line 3—3 of Figure 1;

Figure 4 is a sectional view on the line 4—4 of Figure 1.

In the drawing, I have illustrated the lower portion or base 5 of a hydrant having the usual inlet opening 6 to which the water main is connected. The upper portion of the base 5 is provided with an opening 7 to which the stock or body 8 of the hydrant is secured.

35 As shown in Figures 1 and 2, an annular flange 9 is provided in the upper portion of the base adapted to form a seat for the packing 11 and a valve seat ring 12. The seat ring is preferably provided with screw threads 13 and the opening 7 is correspondingly threaded by means of which the ring may be securely clamped against the packing 11 resting upon the seat 9, thereby providing a watertight joint between the ring and the seat. The flange 9 is suitably bored to receive the lower reduced portion 14 of the seat ring. An annular valve seat is provided at the lower end of the reduced portion 14 of the ring 12. This valve seat is adapted to engage a suitable valve 16, preferably of leather, rigidly mounted upon a valve stem or spindle 17 by the washers 18 and 19 and the nut 21 as shown clearly in Figure 1.

45 An important feature of this invention is

the means provided to prevent waste refuse material such as pebbles, sticks and the like, from clogging the waste water port. The seat ring 12 has an inwardly projecting integral lug 23 provided with a bore to receive 60 a plunger 24 preferably cylindrical in form and of any suitable non-corrosive material, such as bronze. This plunger is adapted to slide vertically in the bore of the seat ring below a cross-head or bar 25 which extends 65 transversely of the hydrant and is centrally secured to the valve stem 17. The upper end of the plunger is adapted to contact with the under side of this crossbar without being attached in any way thereto and consequently the plunger has freedom of vertical movement but is forced down positively in the bore of the seat ring when the valve stem and crossbar are depressed. A port 26 is provided in the wall of the seat ring in radial alignment with the plunger and beneath 70 the bore in the seat ring. This port communicates with an annular groove 27 provided in the wall of the opening 7 and a discharge port 28 is provided in the wall of the hydrant and communicates with the groove 27 for the discharge of the waste water. Thus 75 when the valve 16 is closed and the plunger 24 is in its raised open position as shown in Figure 1, the waste water contained within the stock 8 of the hydrant will flow through the port 26 to the groove 27 and from thence through the outlet port 28 to drain the hydrant of the waste water.

80 In the use of the hydrant with these waste water ports and the plunger for closing the inner port, I have found that waste refuse material such as pebbles, pieces of wood or the like, will be carried by the water into the waste port clogging it and interfering 85 with the proper function of the waste water discharge. I, therefore, provide a reduced extension 24a on the lower end of the plunger which, when the plunger is in its raised position will lie in front of the opening to the discharge port 26 and serve as a seal or guard therefor preventing waste material from being carried into and clogging the port. When the plunger moves to its closed position, this reduced extension will 90 slide down and rest upon the top of the hydrant valve and the waste water discharge port will be closed completely by the plunger and when in its closed position, the pressure 95 of the water on the plunger will force it 100 to close the port 26. The reduced extension 24a will be of a length to prevent the plunger from 105 being forced down so far as to close the port 26 when the valve 16 is closed. The reduced extension 24a will be of a length to prevent the plunger from 110 being forced down so far as to close the port 26 when the valve 16 is closed.

against the wall of the port 26 and positively prevent leakage of water therethrough. The seat ring is also provided with upwardly projecting opposed integral lugs 29 having 5 vertical guideways 31 adapted to receive the ends of the crossbar 25. The bar is adapted to slide vertically in these guideways and the valve stem and valve are thereby guided in their vertical movement.

10 It will be noted in this application that the plunger for controlling the flow of water through the waste port is not connected to either of the parts of the apparatus by which it is operated. It is a free or floating 15 member, may rest upon the top of the hydrant valve, positively moved to an open position when the valve is closed, and allowed to drop or be forced down by the crossbar 25 when the valve is opened. When 20 the valve is closed and the plunger raised, the waste water may flow freely through the port but the entrance of pebbles or waste material therein will be positively prevented. Upon opening the hydrant valve, the 25 stem and crosshead supported thereby will be lowered and the engagement of the crossbar or head with the top of the plunger will force it down across the entrance to the waste port, closing it against the entrance 30 of water as long as the hydrant valve is open. As soon as the valve is raised to its closed position, the plunger will be raised again exposing the waste water port while the extension will prevent the entrance of 35 refuse or pebbles therein.

The plunger being unattached to the moving parts of the hydrant will not be affected by any lateral twist or strain on the valve stem or the crossbar thereon and hence will 40 always be in condition to properly perform its functions, closing the waste water port when the crossbar descends and the valve is opened and exposing the port to allow the escape of water but preventing the entrance of pebbles or refuse therein when the valve is raised to its closed position.

I claim as my invention:

1. A fire hydrant having a valve and seat therefor, a stem for said valve and a waste water port above said valve and a sliding cut-off for said waste port in the path of said valve to be raised thereby, and means carried by said stem and normally separated from said cut-off for positively operating it to close said port when said valve is opened.

2. A fire hydrant having a valve and seat therefor, and a stem for said valve and a waste water port above said valve, a cut-off for said waste port adapted to be raised to an open position by said valve, and a cross member on said stem adapted to engage said cut-off and force it to its closed position when said valve is opened.

3. A fire hydrant having a valve and op-

erating stem and a seat for said valve and a waste water port, a crossbar carried by said stem and guides therefor, and a free or floating cut-off between said valve and crossbar adapted for vertical movement and actuated by contact with the valve and crossbar to open and close said port.

4. A fire hydrant having a valve seat, a valve and operating stem and a waste water port, a crossbar mounted on said stem and having suitable guides therefor, and a cut-off plunger for said waste water port mounted below said crossbar and positively actuated by the downward movement of said bar to close said port without being connected to said bar.

5. In a fire hydrant, a shoe, a stock thereon having a communicating passage between them, a valve seat ring fitting within the passage and having a waste water port, said port having a substantially vertical bore as a guide and entrance orifice, said ring further having a valve seat below said bore, a cutoff comprising a cylindrical plunger vertically movable in said guide and entrance bore, and having a guard at its lower end to bridge the port and prevent entrance of pebbles or refuse, a valve for said seat abuttingly engageable with the cutoff, to alternately translate the same in opposite directions the inner wall of said fitting being cut away to obtain more direct and substantially horizontal flow of water around the guard and into the port, when said valve is closed.

6. In a fire hydrant, a shoe, a stock thereon having a communicating passage between them, a valve seat ring fitting within said passage and having a waste water port and a guide and entrance bore communicating with said port, and further having a lower valve seat, a valve therefor and a stem for said valve, a cutoff mounted to move in said guide bore to open and close said waste water port, said cutoff being cylindrical in form and having a reduced extension at its lower end that is adapted to be positioned in front of and outside the entrance to said waste water port, to prevent entrance of refuse when said cutoff is raised or lowered, the wall of said ring being cut to intersect said guide bore at its intake end, to obtain a more direct flow of water to said port around the reduced extension, when said valve is closed, said valve being abuttingly engageable with the cutoff to alternately translate the same in opposite directions.

7. In a fire hydrant, a shoe, a stock thereon having a communicating passage between them, a valve seat ring fitting within said passage and having a radially extending waste water port and a valve seat, a valve therefor, and a stem for said valve, said seat ring having a vertical bore, a cut-off fitting snugly within said bore but adapted to slide vertically therein across the entrance to said

port to open or close the same, said cut-off being in the path of said valve to be raised thereby when said valve is closed and means mounted on said valve stem to move vertically with said stem, the upper end of said cut-off being in the path of said means to be engaged and actuated thereby to move said cut-off to a closed position when said valve is opened.

- 10 8. In a fire hydrant, a shoe, a stock thereon having a communicating passage between them, a valve seat ring fitting within said passage and having a waste water port and a valve seat, the entrance opening to said port being substantially vertical, a valve for said seat and a stem for said valve, said seat ring having a vertical bore, a cut-off plunger mounted to slide in said bore and open or close said waste water port, the lower end 15 of said plunger being in the path of said valve to be engaged and actuated thereby when said valve is closed, a cross member mounted on said stem and having vertical guides therefor and movable therein vertically with said stem, the upper end of said plunger being below said cross member to 20 be engaged in the downward movement of

said cross member for forcing said plunger downwardly to close said waste water port when said valve is opened.

30

9. In a fire hydrant, a shoe, a stock thereon having a communicating passage between them, a valve seat ring fitting within said passage and having an inwardly projecting integral lug provided with a vertical bore, 35 said seat ring also having a waste water port and valve seat, the entrance opening to said port being substantially vertical, a valve for said seat and a stem for said valve, a cut-off plunger mounted to slide in the bore in said lug and open or close said waste water port, the lower end of said plunger being in the path of said valve to be engaged and actuated thereby when said valve is closed, a cross member mounted on 40 said stem and vertically movable therewith, the upper end of said plunger being in the path of said cross member to be engaged and actuated thereby when said member descends, to close said waste water port when 45 said valve is opened.

40

In witness whereof, I have hereunto set my hand this 6th day of February, 1925.

LEONIDAS P. STOREY.
